US0D1038812S

(12) **United States Design Patent** (10) **Patent No.:** **US D1,038,812 S**
(45) **Date of Patent:** **** Aug. 13, 2024**

(54) **WATCH STRAP**

(71) Applicant: **Shenzhen Binghong Technology Development Co., Ltd.**, Shenzhen (CN)

(72) Inventor: **Yangbing Ou**, Shenzhen (CN)

(73) Assignee: **Shenzhen Binghong Technology Development Co., Ltd.**, Shenzhen (CN)

(**) Term: **15 Years**

(21) Appl. No.: **29/927,554**

(22) Filed: **Feb. 5, 2024**

(30) **Foreign Application Priority Data**

Jan. 3, 2024 (CN) 202430003393.6

(51) LOC (14) Cl. 11-01

(52) U.S. Cl. ..... USPC D11/3

(58) **Field of Classification Search**

USPC D11/1-5; D10/32

CPC A44C 5/00
